(57) **CLAIM**

The ornamental design for “nozzle,” as shown and described.

DESCRIPTION

FIG. 1 is a front perspective view of a “nozzle” incorporating the design of my invention;

FIG. 2 is a top view thereof;

FIG. 3 is a bottom view thereof;

FIG. 4 is a side view thereof;

FIG. 5 is another side view thereof;

FIG. 6 is a rear view thereof;

FIG. 7 is a front view thereof; and,

FIG. 8 is an alternative perspective view showing the nozzle of FIG. 1 but fitted to a connector.

The phantom lines in FIG. 8 illustrates an environment of the design only but does not form part of the design of the claimed invention.
